UNITED STATES PATENT OFFICE

EDWARD J. BRANDT, OF WATERTOWN, WISCONSIN, ASSIGNOR TO BRANDT AUTOMATIC CASHIER COMPANY, OF WATERTOWN, WISCONSIN, A CORPORATION OF WISCONSIN

MONEY HANDLING MACHINE

Application filed May 24, 1924. Serial No. 715,662.

My invention relates to new and useful improvements in money handling machines which have become familiarly known as the "Brandt" type of automatic cashier and the present invention has for its principal object the provision of a machine which may be readily changed from a "payer" basis to a "changer" basis or from a "changer" basis to a "payer" basis, a movable keyboard being provided for this purpose, said keyboard having a plurality of keys bearing designating marks, the keys when depressed engaging suitable mechanism for delivering coins of different denominations from a coin tray or magazine. When on a "payer" basis when a key is depressed coins of different denominations will be ejected from the coin tray of an amount corresponding to the designating mark upon the particular key depressed and when on a "changer" basis coins will be ejected from the coin tray of an amount of the difference between that of the designating mark on the key and one dollar, the machine normally operating on what may be termed a dollar basis although I provide means whereby the machine may be operated on a basis of fractions of a dollar. In other words say that when the machine is operating on a dollar basis and it is desired to deliver change from the coin tray after deducting 17¢ from the dollar the key bearing the designating mark seventeen will be depressed and through suitable mechanism 83¢ will be delivered from the coin tray. If operating on a "payer" basis and the key bearing the designating mark seventeen is depressed coins amounting to 17¢ will be ejected from the coin tray. If the machine is to be operated on a basis of a fraction of a dollar I have provided suitable mechanism which when operated will deliver change from a fraction of a dollar. For example say that it is desired to deliver change from 50¢ after deducting 17¢ then the mechanism to place the machine on a fraction of a dollar basis will be operated to deliver change from 50¢. When the key bearing the designating mark seventeen is depressed then 33¢ change will be delivered from the coin tray.

A further object of the invention resides

in the provision of means whereby the machine may be set to operate either on a "payer" or "changer" basis but which may be moved to perform one transaction on the opposite basis. In other words say that the machine is normally set to operate on a "payer" basis I have provided means whereby the keyboard may be moved so that one transaction may be performed on the "changer" basis and I have also provided means whereby when such single transaction is performed the keyboard will be automatically returned to that position or basis upon which it is set to normally operate.

A further object of the invention resides in the provision of means whereby when the keyboard is set to operate on a "payer" basis the mechanism for throwing the machine on the basis of a fraction of a dollar will be held in inoperative position.

Still another object of the invention consists in providing a plurality of what may be termed double acting keys and ejecting mechanism so that coins will be ejected both when the keys are depressed and when returning to their normal position. In other words I have provided mechanism whereby when a key is depressed it will deliver the amount designated upon the key and will also deliver a like amount upon the upward movement of the key or the movement of the key in returning to its original or normal position. For an example I will say that a key bears a designating mark to deliver five pennies from the coin tray or magazine. When this key is depressed it will deliver five pennies from the coin tray and when it raises or returns to its normal position an additional five pennies will be delivered from the tray. It will thus be seen that I have provided a very quick movement whereby a plurality of coins of a similar denomination may be delivered from the coin tray.

A still further object of the invention resides in the provision of a coin tray or magazine of novel construction, said coin tray or magazine having a plurality of compartments formed by vertically extending partitions, said partitions being detachably connected to a back plate, the tray being removably sup-

ported upon the machine so that when desired it may be removed, with the coins therein, and deposited in a safe or other receptacle over night.

- 5 As another object I provide a novel form of discharge chute for the coins delivered from the tray or magazine, said chute being provided with a slidable bottom or gate which is normally held in closed position but which 10 may be locked in open position, means also being provided whereby a spout may be connected to the chute for delivering the discharged coins directly into pay envelopes or other suitable receptacles.
- 15 As a further object of the invention I construct the bottom of the machine and the operating mechanism at such angles that the keys of the keyboard may be readily seen and the ejecting mechanism is operable without 20 friction and so positioned as to readily eject the coins from the coin tray or magazine, said coin tray or magazine being supported at an inclined position upon the machine so that the coins will be supported at an angle and 25 against accidental displacement from the machine.

With the above and other objects in view, which will appear as the description proceeds, my invention consists in the novel details of construction, and arrangement of parts, described in the following specification and illustrated in the accompanying drawings, and while I have illustrated and described the preferred embodiments of the 30 invention, as they now appear to me, it will be understood that such changes may be made as will fall within the scope of the appended claims.

In the drawings:

- 40 Fig. 1 is a side elevation with parts shown in section.

Fig. 2 is a vertical longitudinal section on the line 2—2 of Fig. 3.

Fig. 3 is a top plan with parts broken away.

- 45 Fig. 4 is a detail view illustrating the shifting mechanism for the keyboard and portions of the rocker arms and keyboard resetting mechanism.

- 50 Fig. 5 is a detail sectional view, with parts shown in elevation, of the coin supporting tray and ejecting mechanism.

Fig. 6 is a rear view of the coin tray.

- 55 Fig. 7 is a side elevation of one of the partitions forming a part of the coin tray.

Fig. 8 is a side elevation of one of the slideable coin ejecting plates.

- 60 Fig. 9 is a view similar to Fig. 5 looking from the opposite side of the machine.

- 65 Fig. 10 is a detail front elevation of the mechanism for placing the machine on a basis for ejecting coins from a fraction of a dollar.

- Fig. 11 is a top plan of a unit to be attached to the machine for delivering a double number of coins upon each operation of the keys.

Fig. 12 is a side elevation of the unit shown in Fig. 11.

Fig. 13 is a horizontal section on line 13—13 of Fig. 12.

Figs. 14 and 15 are fragmental details 70 showing the normal and downward position of the operating keys of the units shown in Fig. 11.

Figs. 16 and 17 are detail sectional views on lines 16—16 and 17—17, respectively, of Figs. 75 12 and 13.

Fig. 18 is a fragmental detail view showing in plan the locking mechanism for the fraction of a dollar keys.

Fig. 19 is a bottom plan of the closure for 80 the coin chute.

Fig. 20 is a plan view with parts in section of the closure for the coin chute.

Fig. 21 is a section on the line 21—21 of 85 Fig. 20.

Fig. 22 is a longitudinal section on the line 22—22 of Fig. 20.

Fig. 23 is a side elevation, with parts in section, of the holding and releasing means 90 for the shiftable keyboard.

Fig. 24 is a section on the line 24—24 of Fig. 23 looking in the direction of the arrows, and

Fig. 25 is a section on the line 25—25 of 95 Fig. 23 looking in the direction of the arrows.

In the drawings 1 indicates the supporting castings of which there is one on each side of the machine, these supporting castings having the legs 2 at each end and the legs 100 having the removable blocks 3 secured thereto. Supported on the castings 1 are the side frames 4 and the bottom plates 5 and 6, the bottom plate 5, as shown, extending downwardly at an angle from the rear end of the machine towards the center and the bottom plate 6, as shown, extending downwardly at an angle from the forward end of the machine towards the center, the inner ends of the plates 5 and 6 meeting as shown. The side frames 4 are connected by the transversely extending rods 7 which extend therebetween.

A set screw 8 passes through one of the side frames and engages in a threaded opening 9 formed in the end of the rod, the opposite end of the rod being exteriorly threaded as shown at 10 to receive an interiorly threaded sleeve 11. A set screw 12 passes through the opposite side frame and engages the interiorly threaded sleeve 11 as shown.

It will thus be seen that an adjustment of the rods may be secured for positioning the side frames or adjusting them one relative to the other. Pivotally connected to the side frames 4 are a plurality of rocker arms 13 which are nested as shown, said rocker arms being supported in normally raised position by means of the coiled springs 14, the upper ends of the coiled springs being connected to the side frames and their lower ends being connected to the rocker arms. Secured

115

120

125

130

to each of the rocker arms 13 is a depending arm 15 which is pivotally connected at 16 to a pusher bar 17 said pusher bar extending parallel with the base plate 5 and having at its forward end the extension 18 which is on a somewhat higher plane and has its forward end downwardly curved as shown at 19. Secured to the base plate 5 is an inverted U-shaped bracket 20 which limits the downward movement of the rocker arms, the horizontal portion of this bracket being somewhat resilient so that when the rocker arms are depressed it will take up jar and thereby protect the operating mechanism as will be readily apparent. The upper edges of the rocker arms are rounded as shown at 21 to form a bearing for the fingers of the operating keys.

The downwardly curved ends 19 formed on the extensions 18 of the pusher bars 17 are pivotally connected at 22 to the slidable plates 23 which are mounted upon the rollers 24 and 25 which are rotatably supported by the vertically extending plates 26 and 27 respectively. The rollers 24 and 25 operate in the elongated openings 28 and 29 formed in the plates 23, said slots allowing the plates to be slid parallel to the bottom plate 6. Secured on opposite sides of the plate 27 are the fibre blocks 30 and 31 a metal plate 32 being secured to the outer face of the block 31 and having notches 33 formed in the upper edge thereof. The plates 23 have the downwardly extending projections 34 and 35 formed on the lower edge, the projection 34 when the plate 23 is in its rearward position engaging the fibre block 30 and the projection 35, when the plate is in its forwardmost position extending through the notches 33 in the plate 32 and engaging the fibre block 34. An upwardly extending projection 36 is formed on the forward upper edge of the plate 23 and forms a shoulder 37 for a purpose which will be presently brought out. A projection 38 is formed on the forward lower edge of the plate 23 and normally rests upon the block 39 secured to the forward face of the plate 26.

Pivots connected at 40 to each of the sliding plates 23 is a coin ejecting finger 41 which passes through the plate 42 at the front of the machine and through a slot 43 formed in the lower edge of the coin tray *a*. Pivots connected at 44 to the fingers 41 is a second finger 45 which also passes through the opening in the plate 42 and the opening 43 in the coin tray. This lower finger 45 normally rests on and is slidable upon the plate 46 secured to the inwardly extending portion 47 of the upwardly extending flange 48 which is formed on the forward edge of the bottom plate 6. A bolt 49 passes through the fingers 41 and 45 and receives the nut 50 which engages the lower face of the finger 45. A coiled spring 51 surrounds the bolt 49 between the fingers and normally holds them in spaced relation so that the finger 45 will en-

gage the plate 46 and the finger 41 will be in position to eject the coins 52 which are supported in the coin tray *a*.

The coin tray *a* comprises the back plate 53, the bottom 54 and the vertically extending partitions 55 which provide a plurality of compartments of different sizes to receive stacks of coins of various denominations. Formed in the rear face of the back plate are the longitudinally extending grooves or recesses 56 and 57, the groove or recess 56 being adjacent the upper edge and the groove or recess 57 being adjacent the lower edge. The vertically extending partitions 55 are formed on their rear edges with the vertically spaced lugs or projections 58 and 59 which pass through openings formed in the back 53 and into the grooves or recesses 56 and 57. The lugs or projections 58 and 59 have openings therein to receive the rods 60 and 61 which extend longitudinally of the grooves or recesses 56 and 57 and secure the partitions 55 to the back plate 53. Secured to the rear face of the back plate 53, beneath the groove or recess 57, by means of the clamp plates 62, are the longitudinally extending rods 63 and 64. Carried on the rod 63 for swinging movement are the longitudinally spaced coin engaging members 65, these members extending through the openings 43 formed in the back plate 53 so that one of the coin engaging members will be engageable with each of the stacks of coins carried in the tray. The coin engaging members 65 have the openings 66 formed therein to receive the rod 64, said rod limiting the swinging movement of the members in either direction. The rear ends of the coin engaging members are rounded as shown at 67 to engage locking levers to be later described. Plates 68 are secured to the upper edge of the coin tray to engage over the portion 69 of the machine to hold the tray in position. As shown eight stacks of coins will be supported by the tray. Reading from the lefthand side of the tray the first three stacks will be pennies, the fourth stack nickles, the fifth and sixth stacks dimes, the seventh stack twenty-five cent pieces, and the eighth stack fifty cent pieces. The plungers operating in the second and third stacks of pennies will deliver two at a time.

Pivots mounted on the transversely extending rod 70 are the locking levers 71 there being one locking lever for each of the sliding plates 23. Each of the locking levers comprises a substantially vertically extending portion 72 and a substantially horizontal portion 73, the portion 73 having a roller 74 mounted at its rear end. The vertically extending portion of the locking lever extends in position to be engaged by the rounded portion 67 of the coin engaging member 65 and when there are coins in the particular compartment of the coin tray the coin engaging

member will be held in its rearwardmost position, as shown in Fig. 5 of the drawings and will hold the rear or roller end of the locking lever in raised position so that the plate 23 may be freely slid. When the stack of coins becomes low the coin engaging member 65 will swing into the coin compartment and thereby allow the rear or roller end of the locking lever to fall and engage the shoulder 37 formed on the sliding plate 23. When in this position the plate 23 cannot be slid to eject coins. It will be seen that the edges of the coins engage the forward edge of the coin engaging member and as has been previously stated normally holds this member in its rearwardmost position but when the stack of coins becomes low the coin engaging member will swing inwardly over the tops of such coins as might remain in that particular stack. When the sliding plate 23 is held in locked position notice will be given to the operator of the machine that a new supply of coins is necessary. In order to release the locking levers from their locking engagement with the slideable plates 23 I provide the rocker rod 75 which is pivotally mounted in the side frames of the machine and extends beneath the horizontal portions of the locking levers as more particularly illustrated in Figs. 9 and 10 of the drawings. Secured to the base plate 6 is a bracket 76 which extends vertically and is provided with the elongated openings 77 and 78, the opening 77 being formed with the right angle extension 79 at its upper end. A bar 80 extends through an opening 81 formed in the base plate 6, adjacent the forward end of the machine, and parallel with the bracket 76. The lower end of this bar 80 is bent at right angles as shown at 82 to form a portion adapted to be engaged by the fingers of the operator of the machine to slide the bar vertically. The upper end of the bar is provided with the right angle extension 83 which extends beneath the rocker rod 75 and in engagement therewith. Formed on or secured to the bar 80, intermediate the ends, are the headed studs or projections 84 and 85, the stud or projection 84 operating in the opening 77 and the stud or projection 85 operating in the opening 78 of the bracket. As more particularly illustrated in Fig. 9 of the drawings the headed studs or projections 84 and 85 normally engage the lower edges of the openings 77 and 78 and when the locking levers 71 are in position with the roller 74 engaging the shoulders 37 of the slideable plates 23 the substantially horizontal portions of the locking levers will engage on the rocker rod 75. When it is desired to raise the locking levers so as to release the slideable plates 23 the operator engages the extension 82 on the lower end of the bar 80 and pushes the same upwardly so that the stud or projection 84 will be received in the right angle extension 79 of the opening

77. When the lug or projection 84 is in the right angle extension 79 of the opening 77 the bar 80 will be held in its raised or uppermost position. As the bar 80 is raised the right angle extension 83 engaging the rocker rod 75 will swing the same and thereby raise the locking levers from engagement with the slideable plates 23. It will be understood that when the coins become low in the tray that it will be desired to release the locking levers so that the slideable plates may operate to eject all of the coins that are in the tray without replenishing the stack. Of course, it might also be desirable to release the locking levers prior to introducing the coins into the tray. After the coins are ejected from the coin tray they will drop into the chute 86 which is formed or secured on the forward end of the machine, the bottom of the chute being downwardly inclined from opposite ends as shown at 87 and leading to the central opening 88. Secured to the underside of the machine and extending forwardly to a point beneath the central opening 88 of the chute 86 is a frame having an end portion 89 and side arms 90 said side arms being provided in their inner faces with the longitudinally extending grooves 91 in which operate a slideable plate 92 which normally extends beneath the central opening 88 of the chute and forms a closure therefore. Formed on the bottom of the plate 92 is a substantially semi-circular depending flange 93 which forms a finger engaging portion for engagement by the operator for sliding the plate longitudinally of the frame to remove the plate from beneath the opening 88 and allow the coins to pass therethrough into the hand of the operator or in a suitable receptacle provided for the reception of the coins. The plate 92 is formed on its rear end with the arms 94 which have their ends bent upwardly at right angles to form the projections 95 these projections adapted, when the plate is slid rearwardly of the frame to engage the bumpers 96 which may be of rubber or other suitable resilient material, they being connected to the end 89 of the frame. Supported between the end 89 of the frame and the rear wall of the chute 86 is a cylinder 97 which extends inwardly towards the forward end of the frame as more particularly illustrated in Fig. 20 of the drawings. Carried in this cylinder or tube 97 is a coiled spring 98 one end of which engages the end 89 of the frame and the opposite end engages an upwardly extending projection 99 formed on or secured to the upper face of the plate and operable in a longitudinally extending slot 100 which is formed in the bottom of the cylinder or tube. The coiled spring 98 normally holds the plate in its forwardmost position but when the plate is slid rearwardly by the operator the spring will be compressed and automatically return the plate to its forwardmost position

when released by the operator to close the opening 88 in the chute 86. An opening 101 is formed in one of the side arms 90 of the frame and pivotally connected to the upper 5 surface of the plate 92, adjacent one longitudinal edge thereof, is a latch 102 said latch having on its rear end a right angle projection 103 and on its forward end a projection 104 which carries a downwardly extending 10 pin or lug 105. When it is desired to hold the plate in its rearward position to allow the coins to freely pass through the opening 88 the latch 102 is swung so that the extension 103 thereof will engage in the opening 101 15 and thereby hold the plate against automatic return by the coiled spring. When it is desired to release the plate the pin or lug 105 will be engaged to swing the latch to release the extension or projection 103 from the opening 101 and this will allow the spring to return the plate to its closing position beneath the opening 88. Extending inwardly from the end 89 of the frame is a pin 106 which passes through one end of the cylinder or tube 25 97 and through a portion of the spring 98 thereby aiding in supporting the spring as is more clearly illustrated in Fig. 22 of the drawings. Formed in each side arm 90 of the frame, adjacent the forward end thereof, is 30 an opening 107 for securing certain attachments to the chute, one of these attachments being indicated in dotted lines 108 and being in the form of an auxiliary chute which is more particularly adapted for discharging 35 the coins directly into an envelope. It will be understood that such an auxiliary chute will be of particular advantage in making up pay rolls where the pay is delivered to the employee in an envelope. When this auxiliary chute is used the end thereof may be positioned into the mouth of the envelope and the coins which are delivered from the machine will pass directly into the envelope. The auxiliary chute will be provided on opposite sides with spring controlled plungers 40 110 which will enter the openings 107 formed in the side arms 90 of the frame for supporting the auxiliary chute. While I have described the attachment in the form of an auxiliary chute for delivering coins directly 45 into pay envelopes or the like it will be understood that the openings in the sides of the frame might be equally as well adapted for holding various forms of attachments for delivering the coins from the main coin discharging chute into different positions or different forms of receptacles.

For operating the coin ejecting mechanism I provide a plurality of keys which when 50 depressed operate the coin ejecting mechanism to eject different combinations of coins, the keys being carried by a slideable keyboard which sets at an angle so that the designating marks upon the keys may be easily 55 read by the operator. The keyboard is mounted upon rollers so as to be freely movable into its different positions without undue friction. As has been previously stated when the keyboard is in its raised position the machine will operate on a "changer" basis 70 and when the keyboard is in its lowered position the machine will operate on a "payer" basis.

The keyboard comprises the top plate 111 and the bottom plate 112 spaced therefrom the top plate being supported for sliding movement upon the rollers 113 which are secured to each of the side frames 4 of the machine. As shown more particularly in Fig. 2 of the drawings the front supporting 75 rollers will be on a somewhat lower plane than the rear supporting rollers so as to support the keyboard in slightly inclined position so that, as has been previously stated, the designating marks upon the several keys forming a part of the keyboard may be easily read by the operator. In order to prevent lateral or side movement of the keyboard with respect to the frame of the machine and to aid in preventing undue friction in the 80 sliding movement of the keyboard I secure to the upper plate the longitudinally spaced transversely extending bars 114 to opposite ends of which are secured the rollers 115 which engage the sides of the frame. It will 85 thus be seen that by providing the supporting rollers and the rollers on the ends of the rods which engage the sides of the frame that the keyboard may be raised and lowered at the will of the operator without undue friction. Secured to one of the side frames 90 95 100 is a block 116 which is adapted to be engaged by the arms 117 which are secured to the keyboard, these arms engaging the block to limit both the upward and downward movement of the keyboard. The edge of the upper plate 111 will be cut away as shown at 118 so as to leave space to prevent the block 116 from engaging with the plate. The upper plate 111 is also cut away, adjacent one edge, as shown at 119 to form a sight opening through which will show either "Chg.", when the keyboard is in raised position, or the word "Pay", when the keyboard is in lowered position, so as to indicate to the operator whether the machine is set for operation on the "changer" or "payer" basis. Both the upper plate 111 and the lower plate 112 are provided with a plurality of openings, those in the lower plate being in alignment with those in the upper plate, to receive the substantially vertically extending key bars 120, said key bars having on their upper ends the buttons or finger pieces 121 bearing designating marks preferably in the 110 form of numerals. Each of the key bars is provided on its edges with a cut-out or notched portion 122 and a coiled spring 123 surrounds each of the bars, the upper end of the spring engaging the shoulder formed 115 120 125 130

by the cut-out or notched portions 122 and the lower end engaging the upper face of the bottom plate 112 so as to normally hold the key bars in their raised positions. Each 5 of the key bars is formed on its lower end with a horizontal extension 124 which in turn has a plurality of downwardly extending fingers or projections 125 which will be spaced in such a manner as to engage the desired 10 rocker arms to eject the proper combination of coins from the coin tray. The fingers or projections 125 are of such a width that they may be received between the rocker arms for a purpose which will presently be apparent. 15 The fingers or projections 125, when the keyboard is in raised position, or on a "changer" basis engage a certain group of the rocker arms and when in a lowered position or on the "payer" basis other projections or fingers will engage other groups of rocker arms. 20 Those projections or fingers not engaging the rocker arms being received in the space between the rocker arms and being thereby inoperative. The upper edges of the rocker arms being rounded will allow the ends of the fingers or projections 124 to properly operate to depress the rocker arms and thereby operate the pusher bars and associated coin ejecting mechanism the angle at which the 25 coin bars are arranged relative to the slide- able plates 23 and associated coin ejecting mechanism being such as to allow the parts to freely slide and the coin ejecting fingers to properly engage the coins which are sup- 30 ported at an angle in the coin tray to prevent accidental displacement of the coins in the several stacks.

At times it is desirable to quickly receive double the amount which is indicated on the 40 keys and in order that this may be done I have provided certain keys and associated mechanism so that the amount designated upon the keys will be delivered from the coin tray upon the depression of the keys and a 45 similar amount will be delivered from the coin tray upon the upward movement of the key or upon the return movement of the key to its original or raised position. These particular keys are carried by a separate unit 50 which when secured to the upper plate 111 of the keyboard forms a continuation thereof and in fact the supporting rollers 113 which are on the frame of the machine adjacent this particular unit engages beneath the unit 55 which is slidable thereon. The unit comprises a plate 126 which on one edge is formed with the vertically extending flange 127 the upper edge of which is bent at right angles to form the horizontal portion 128 which is 60 provided with the longitudinally spaced openings 129 whereby the unit may be secured to the plate 111. As shown more particularly in Fig. 3 of the drawings the trans- 65 versely extending bars 114 extend over the upper face of the plate 126, the plate being

formed with one longitudinal edge at an angle to allow the proper positioning of the keys. A plurality of substantially vertically extending key bars 130 are carried by the plate 126 and extend through the openings formed therein, certain of the key bars extending on one side of the vertically extending plate 131 depending from the plate 126 and other key bars extending on the opposite face thereof. Each of the key bars 130 operated by the keys 150, 151, 153, 154, and 155 is formed on one vertical edge with a rack 132 which meshes with a gear wheel 133 rotatably connected to the depending plate 131 by means of the screw or rivet 134. As shown there are a plurality of gear wheels secured to each face of the depending plate 131 the gear wheels on each face of the plate being longitudinally spaced as more clearly illustrated in Fig. 12 of the drawings. While any number of gear wheels may be used as required the unit which is disclosed in the drawings comprises five of such wheels three being mounted on one face of the depending plate and two being mounted on the opposite face thereof. A description of one of the gear wheels and its associated parts will suffice for all. Each of the gear wheels has the studs or pins 135 and 136 secured to one face thereof, these studs or pins being so arranged as to extend on different sides of the vertical center of the gear securing pins or rivets 134 as more clearly illustrated in Fig. 12 of the drawings. A coiled spring 137 has one end secured to the plate 126 and the opposite end connected to the key bar 130 so as to normally hold the key bar in raised position. A plate 138 is carried by each of the screws or rivets 134 being positioned between the associated gear wheel and the face of the plate 131 these plates being provided with an elongated vertically extending opening 139 whereby the plate may be moved vertically. Each of the plates 138 is also provided with a foot or extension 140 which is adapted to engage the rocker arms for operating the coin ejecting mechanism. A coiled spring 141 has one end secured to the plate 126 and the opposite end connected to the plate 130 so as to normally hold the plate in raised position. Pivotal- 110 connected to the plate 138, at 142 and 143 respectively are the vertically extending dogs or arms 144 and 145 the upper ends of these dogs or arms being respectively in a position to be engaged by the pins or studs 135 and 136 when the gears 133 are operated, the upper ends of the arms or dogs being drawn inwardly towards one another by means of the coiled spring 146 which has its ends secured to the dogs. The inward movement 115 of the dog 144 is limited by the pin 147 and the inward movement of the arm or dog 145 is limited by the pin 148, these pins 147 and 148 being formed on or secured to the depending plate 131. Secured to the upper ends of 120

the key bars are the finger pieces or buttons which bear designating marks showing the coins which will be ejected from the coin tray upon each operation of the key bar. The buttons or finger pieces are shown at 149, 150, 151, 152, 153, 154 and 155. When the key 149 is depressed five pennies will be ejected upon the downward movement of the key bar. When the key 150 is operated five pennies will be delivered from the coin tray on each movement of the key bar. In other words when the key 150 is depressed it will operate the gear 133 associated therewith and will rotate the same in the direction indicated by the arrows in Figs. 12 and 14 of the drawings. This movement will cause the pin or projection 135 to engage the upper edge of the dog or arm 144 and force the same downwardly with the plate 138 and the lower edge of the plate will engage the rocker arms to operate in turn the ejector fingers associated with the first three stacks of coins which are pennies. One penny will be ejected from the first stack and two pennies from both the second and third stack. When this downward movement of the key has been completed the plate 38 will be returned to its original position and the upper end of the dog or arms 145 will be positioned beneath the pin or projection 136. As the key is released and raises the gear wheel 133 will be rotated in the direction indicated by the arrow in Fig. 15 of the drawings and the pin or projection 136 engaging the upper end of the arm or dog 145 and will again lower the plate 138 to engage the rocker arms for again ejecting five pennies as has been previously described. It will thus be seen that when the key is pressed downward five pennies will be ejected and then when the key is released and moved upwardly it will again eject five pennies. When the key 151 is operated one nickel will be delivered upon each movement of the key bar in the same manner as described for the operation of the key 150. When the key 152 is operated two dimes will be delivered upon the downward movement of the key bar. When the key 153 is operated two dimes will be delivered from the coin tray in each direction of the key bar in the same manner as described for the operation of the key 150. When the key 154 is operated one quarter will be delivered upon each operation of the key bar and when the key 155 is operated one 50¢ piece will be ejected from the coin tray upon each movement of the key bar in the same manner as set forth for the operation of the key 150. It will thus be seen that I have provided quick and easy means for ejecting a plurality of coins from the coin tray a combination of coins being ejected upon the downward movement of the key bar and the same combination ejected upon the upward movement of the key bar.

When the key bars are in their normal or raised positions the studs or pins 135 and 136 will be in the position shown in Fig. 12 of the drawings it being noted that the stud or pin 135 will be positioned above the upper end of the arm or dog 144 and the stud or pin 136 will be positioned in engagement with the inner vertical edge of the arm or dog 145 intermediate the ends thereof. When the key bar is depressed the rack 132 meshing with the gear 133 will rotate the gear in the direction indicated by the arrows in Figs. 12 and 14 of the drawings so that the stud or pin 135 will engage the upper end of the arm or dog 144 and thereby lower the plate 138 so that the arm or extension 140 will engage the desired rocker arms 13 to eject the coins from the tray. This movement of the gear wheel 133 raises the stud or pin 136 to a position above the upper end of the dog or arm 145. As the key bar starts to return to its normally raised position it naturally rotates the gear 133 in the opposite direction or in the direction indicated by the arrow in Fig. 15 of the drawings and allows the plate 138 to be raised by the coiled spring 141 until the stud or pin 136 engages the upper end of the arm or dog 145. The continued movement of the gear wheel forces the arm or dog downwardly and carries with it again the plate 138 which ejects the same number of coins as has been ejected upon the downward movement of the key bar. When the key bar reaches substantially its uppermost position the stud or pin 136 will move from the end of the arm or dog 145 and allow the plate 138 to again be raised to its original position by the coiled spring 141. As has been previously stated the coiled spring 141 acts to raise the key bar to its original position after the button or finger piece associated therewith has been released by the operator. It will be understood that while the operation of each of the key bars ejects a difference combination of coins from the coin tray nevertheless the movement of the several associated parts will be the same and it might be further stated that the same combination of coins will be ejected from the coin tray by the keys of the just described unit where the machine is operating on a "change" or on a "pay" basis. The plates 138 are of such a length as to extend over a number of the rocker arms and will operate to discharge the same number of coins whether the machine is on a "changer" or "payer" basis.

It will be understood that the key bars operated by the keys 149 and 152 are not what might be termed double acting but these two keys merely eject the coins upon the downward movement of the key bars. With the key bars operated by the keys 150, 151, 153, 154 and 155 coins are ejected on both the downward and upward movements of the key bars.

For shifting the position of the keyboard

from a "changer" to a "payer" basis or from a "payer" to a "changer" basis I have provided a lever which is operable beneath the bottom plate 5 in easy reach of the operator of the machine. The lever is indicated at 156 and at its inner end is connected to a pin 157 which passes through the bottom plate 5. A downwardly extending knob 158 is formed on or secured to the outer end of the lever for engagement by the operator. Secured to the upper end of the pin 157, above the bottom plate 5, is a lever 159 which is of less length than the lever 158 as is more particularly illustrated in Fig. 4 of the drawings. Extending upwardly from the free end of the lever 159 is a stud or projection 160 to which is connected one end of a coiled spring 161 the opposite end of the spring being secured in an eye 162 formed adjacent the lower end 20 of a substantially vertically extending rod 163, the upper end of said rod 163 being secured to the upper plate 111 of the keyboard by means of a screw 164 or other suitable fastening means. Formed in the bottom 25 plate 5 is an arcuate shaped opening 165 through which extends a pin 166 which is secured to the levers 156 and 159. The movement of the levers is limited by the engagement of the pin 166 with the ends of the opening 165. The lever 156, adjacent the free or outer end, operates in a guide which is secured to the underside of the bottom plate 5 by means of the screws 167 or other suitable fastening means. This guide comprises the bottom plate 168 and the top plate 169 which receive therebetween, at the ends, the spacing strips or blocks 170 which space the top and bottom plates apart a sufficient distance to allow the lever 156 to freely operate therebetween. As shown more particularly in dotted lines in Fig. 4 of the drawings the top and bottom plates of the guide are arcuate in shape and the top plate 169 is provided with a plurality of longitudinally 30 spaced openings 171 adapted to receive a projection 172 formed on the upper face of the lever 156, said projection 172, when received in one of the openings 171, holding the lever in its adjusted position. Secured to the 35 upper surface of the bottom plate 5, adjacent the rear edge thereof, is an angle bracket 173 carrying the adjusting screw 174 which extends through the vertical portion thereof, said adjusting screw passing freely through 40 the bracket and being adjusted by means of the thumb nut 175 which is carried thereby and engages one face of the bracket. The adjusting screw is formed on one end with a perforation 176 in which is connected one 45 end of a coiled spring 177, the opposite end of the coiled spring being connected in an eye 178 formed in the rod 163 above the eye 162.

When the lever 156 is swung rearwardly of the machine it will carry with it the 50 relatively short lever 159 and the coiled spring

161 will draw the keyboard towards the rear of the machine. The lever 156 being of a spring construction will position the projection 172 in one of the openings 171 and the lever will be held in its adjusted position. When in this rearward position the keyboard is on a changer basis and when it is desired to change to a "payer" basis the lever 156 is swung inwardly and carries with it the lever 159. This movement of the levers allows the coiled spring 161 to draw or push the keyboard downwardly, the downward movement of the keyboard being aided by gravity as the keyboard is mounted, as has been previously stated, at an angle. When the keyboard is in its lowered position or on the "payer" basis the coiled spring 177 will be expanded or placed under tension and this spring will aid in returning the keyboard to its uppermost position when the lever 156 is moved for that purpose. In other words the spring 177 acts more or less as a balance spring and for automatically returning the keyboard to raised position when said board is moved into lowered position for one operation only in a manner as will be later described.

As has been previously described it is often desired that when the keyboard is set on a "changer" basis for permanent operation that the keyboard be moved for a single operation 95 on the "payer" basis or when set for permanent operation on a "payer" basis that it be moved for a single operation on the "changer" basis. When such an emergency arises it will be apparent that some means should be provided for automatically returning the keyboard to that basis upon which it is set for permanent operation. I have provided such means whereby the keyboard may be moved for a single operation on either of its basis and which will be automatically returned to its permanently set basis after the single desired operation has been completed. Secured to one of the side frames 4 of the machine are the vertically spaced screws or 100 bolts 179 upon which are mounted a vertically extending plate 180, said plate having the elongated openings 181 through which the screws pass. Intermediate the openings 181 is an elongated opening 182, a lug or projection 183 being formed at the lower end thereof. Secured to this lug or projection 183 is one end of a coiled spring 184, the opposite end of the coiled spring being secured to an eye 185 which is formed on or 105 secured to the side frame 4. This coiled spring 184 normally holds the plate 180 in its raised position. Formed on one vertical edge of the plate 180 is the right angled projection 185a which carries the roller 186, said roller projecting from that face of the lug or projection adjacent the side frame 4 for a purpose which will be presently described. Formed on the upper end of the plate 180 is the vertically extending pro- 110

jection 187, this projection being preferably positioned adjacent the vertical center line of the plate. Secured to the underside of the top plate 111 of the keyboard, by means of the rivets or other suitable fastenings 188 is a flat spring 189 the free end of which will normally be spaced from the bottom of the plate. Extending upwardly from the spring, and through the plate 111, is the knob or finger piece 190 and secured to the underside of the 10 spring is a block 191 having the recess 192 formed in its under face. Mounted in the recess 192 is a roller 193, said roller being of such a diameter as to leave a space 15 on each side thereof of a sufficient width to receive the projection 187 formed on the upper end of the plate 180.

Pivottally connected at 194 to the side frame 4 and between the inner face of said side 20 plate and the slidable plate 180 is a latch 195, one end of which is beveled as shown at 196 and the opposite end is reduced as shown at 197 and extends over the top of the roller 186 and normally in contact therewith. Se- 25 cured to the extension 197 is one end of a coiled spring 198 the opposite end of the spring being secured to a projection 199 formed on the frame. This spring 198 has a tendency to normally hold the extension 30 197 in substantially horizontal position the upward movement thereof being limited by a pin 200 extending inwardly from the side frame 4.

Extending upwardly from the bottom 35 plate 5 are the brackets or standards 201 and 202 the bracket or standard 201 having the inwardly extending horizontal pin 203 and the bracket or standards 202 having the inwardly extending horizontal pin 204. Car- 40 ried by the pins 203 and 204 for vertical swinging movement is the frame 205, a coiled spring 206 being positioned on the pin 203 and engaging the inner face of one arm of the frame 205 as is more clearly shown in 45 Fig. 4 of the drawings. The opposite end of the coiled spring is engaged by a washer 207 which is held upon the pin by means of the nut 208. The coiled spring 206 not only al- 50 lows for a slight longitudinal movement of the frame between the pins but also normally holds the frame 205 in raised or substantial- 55 ly horizontal position. Secured to the frame 205 and extending beyond one end thereof is the bar 209 to the outer end of which is se- 60 cured a plate 210 to which the bell crank lever 211 is pivotally connected at 212. Secured to the vertical arm of the bell crank lever 211 is one end of a coiled spring 213 the opposite end of the spring being con- 65 nected at 214 to the plate 210. This coiled spring 213 normally holds the horizontal arm of the bell crank lever 211 in engagement with the upper surface of the latch 195. The frame 205 and the extension bar 209 are posi- 70 tioned beneath the rocker arms 13 as more

clearly illustrated in Fig. 4 of the drawings so that when the rocker arms are depressed they in turn will depress the frame and its associated parts.

Assuming that the machine is set for operation on a "payer" basis the lever 156 will be swung towards the forward end of the machine so that the keyboard will be in its lowered position. It is desired to make a single operation on the machine on a "changer" 75 basis and to do this the knob or finger piece 190 will be engaged and raised to disengage the member 191 from the projection 187 and then the keyboard will be slid rearwardly of the frame or in its uppermost position. 80 When in this position the knob or finger piece 190 is released and the projection 187 on the upper end of the plate 180 will be received on the forward side of the roller 193 as is quite clearly illustrated in Fig. 23 of the 85 drawings. The proper key of the keyboard is depressed for making change and upon the depression of the rocker arms 13 it in turn will depress or lower the frame 205. As the frame 205 is lowered the horizontal 90 arm of the bell crank lever 211 will ride over the beveled end 196 of the latch 195 without causing movement of the plate 180. As the rocker arms raise, after the coins have been ejected from the coin tray, the coiled spring 95 206 will raise the frame 205 and the bell crank lever 211 will engage beneath the end of the latch 195 and swing said latch on its pivot 194. This will lower the extension 197 which 100 engaging the roller 185 will lower the plate 180 and remove the projection 187 on the top of said plate from engagement with the roller 193. This will allow the keyboard to drop, by gravity, in its originally set position to 105 operate on the "payer" basis. If the machine is set for permanent operation on a "changer" basis the action will be just the reverse. When the machine is on the "payer" basis and is temporarily set to "changer", the lever 156 will be in its forward position, the spring 110 161 will be slack, and the spring 177 will not be so strong as to prevent the keyboard from falling back to its "payer" position. When, however, the machine is permanently set as 115 a "changer", the lever 156 will be in its rear- 120 ward position, tensioning the spring 161. Then if the keyboard be shifted temporarily to its lower or "payer" position, the combined tension of the spring 177 plus the spring 161 will be sufficient to raise it, against the force of gravity, back to its "changer" position.

As has been previously stated when the machine is set on a "changer" basis it normally delivers change from a dollar but at 125 times it may be desired to deliver change only from 25¢, 50¢, or 75¢. In order that this may be done I have provided the keys 215 and 216, the key 215 having the downward extension 217 and the key 216 having the downward 130

extension 218 provided with a horizontal portion 218' adapted to engage the upper surface of the coin ejecting finger 41 which operates in the compartment of the coin tray containing the stack of 50¢ pieces and to lower this finger so that when any one of the keys of the keyboard is depressed it will not operate to eject a 50¢ piece from the coin tray. The lower end of the extension 217 of the key 215 is provided with the horizontal portion 219 which extends over and is adapted to make inoperative those coin ejecting fingers which operate to eject both a 50¢ piece and a 25¢ piece, so that when the key 215 is depressed the change will be made only from 25¢ or 75¢ as desired. The key 215 is normally held in its raised position by means of a coiled spring 220 and the key 216 is normally held in raised position by the coiled spring 221. Formed adjacent the lower end of each of the extensions 217 and 218 of the keys are the vertically spaced openings 222 and 223, these openings being adapted to receive the projections 224 formed on the frame 225 which is pivotally connected to the brackets or standards 226 which are secured to the bottom plate 6. This frame 225 is normally held in raised position by the coiled springs 227 with the projections 224 received in the lower openings 223 of the key extensions. When one of the keys is depressed it will engage the beveled upper surface of the projection 224 and allow the projection to be received in the upper opening 222. When in this position the coin ejector fingers will be thrown into inoperative position as has been previously described. Formed on the frame 225 are the inwardly extending portions 228 the lower surfaces of which are rounded as shown at 229 to be engaged by the swinging frame 230. The sliding plates 23 on their forward movement will engage the swinging frame 230 and throw the projection 224 out of the openings 222 in the downwardly extending portions 217 and 218 of the keys 215 and 216 thereby allowing the keys to be raised by their respective coiled springs. In other words where the "changer" is to be operated to eject change from 25¢, 50¢ or 75¢ it will only act on this basis for a single operation and the keys are returned to their normally raised position after such single operation. If change is to be delivered on either the 25¢ or 75¢ basis the key 215 will be operated. This will cut out ejection of coins from the 50¢ chute and the 25¢ chute. Now say a person gives a 25¢ piece in payment of the purchase and a 5¢ piece is to be taken therefrom by depressing the proper key 20¢ change will be given. If the machine is set to operate on a 75¢ basis and the purchase is 55¢ by depressing the 55¢ key 20¢ change will be delivered. In other words it would never be necessary to operate on a 75¢ basis if the purchase was less than 55¢. If the purchase was

50¢ the person would tender a 50¢ piece in payment and if the purchase was above 75¢ naturally the person would tender a dollar in payment.

It will be appreciated that when the machine is operating on a "payer" basis that it will be desirable to provide some means to prevent accidental operation of the keys 215 and 216. For this purpose I provide the extension 231 which is carried by the sliding keyboard and this extension is adapted to engage beneath the projections 232 formed on the rear faces of the downward extensions of the keys. When the keyboard is lowered to a "payer" basis the extension 231 engaging beneath the projections 232 will prevent accidental operation of the keys 215 and 216.

From the above detail description it will be seen that I have provided a novel form of machine which, as has been previously stated, may operate either as a "payer" or as a "changer". The plates 124 which are connected to or form a part of the keys 120 are provided with the proper number of projections so as to operate the proper number of rocker arms to eject the proper combination of coins. There will be a sufficient number of these projections to engage the rocker arms in whichever position the keyboard might be and those projections which are not being used will be received, when the keys are depressed, between the rocker arms. As an example if the machine is set to operate on a "changer" basis and change is to be made after deducting 25¢ from a dollar the 25¢ key will be depressed and will operate the rocker arms to deliver a 50¢ piece and a 25¢ piece from the coin tray. If the machine is operating on a "payer" basis when the key bearing the designating mark 25¢ is depressed on that rocker arm will be operated to eject a 25¢ piece from the coin tray. As a further example I might describe the operation of the key bearing the designation 39 on both a changer or payer basis. With the keyboard mounted on a changer basis and a purchase amounting to 39¢ is made then the 39¢ key will be depressed to give 61¢ in change. Depression of the 39¢ key will eject a penny from the first stack of coins, a dime from the fourth stack of coins, and a 50¢ piece from the eighth stack of coins. When the keyboard is shifted to operate on a payer basis it will be desired to eject 39¢ when the 39¢ key is depressed. With the depressing of the key, when on a payer basis, two pennies will be ejected from each of the second and third stacks of coins, a dime from the sixth stack of coins, and a 25¢ piece from the seventh stack of coins. The advantages of such a machine as I have provided will be readily apparent, when it can be seen that it can be used, for making change, but when making up pay rolls or the like it may be changed onto

a "payer" basis and deliver the proper coins for paying a certain amount. It also has particular advantage in the fact that when the machine is set for operation on one or the other basis the keyboard may be shifted to make a single operation on the other basis and will be automatically returned to its permanent basis so that no error will be made. In other words it can be appreciated that if automatic means were not provided for returning the keyboard to its originally set position the operator might forget and make a number of transactions on the temporary basis.

15 I have also provided means whereby attachments may be connected to the machine so that the coins may be delivered directly into a receptacle such as an envelope and have also provided means whereby, for quick operation, a duplicate number of coins may be ejected upon a single operation of the keys. These particular keys will operate in the same way whether the machine is on a "payer" or on a "changer" basis.

20 25 Having fully described my invention what I claim as new and desire to secure by Letters Patent is:

1. A money handling machine comprising a coin tray, means for ejecting the coins from the tray, and a bodily shiftable keyboard for operating the coin ejecting means.

2. A money handling machine comprising a coin tray, means for ejecting the coins from the tray, and a shiftable keyboard for operating the coin ejecting means, said keyboard when in one position operating the coin ejecting means for ejecting certain combinations of coins from the tray and when shifted into another position ejecting another combination of coins from the tray.

3. A money handling machine comprising a coin tray, means including a plurality of ejectors for ejecting the coins from the tray; a shiftable keyboard for operating the ejectors, means for operating a predetermined combination of ejectors when the keyboard is in one position and means for operating another predetermined combination of ejectors when the keyboard is in another position.

4. A money handling machine comprising a coin tray, means including a plurality of ejectors for ejecting the coins from the tray, and a shiftable keyboard carrying a plurality of keys which when depressed operate the coin ejectors, each key being provided with a designating mark, the key when depressed while the keyboard is in one position delivering coins from the tray in such an amount equal to the difference of the designating mark on the key and one dollar and when depressed while the keyboard is in another shifted position delivering coins from the tray equal to the amount of the designating mark on the key.

5. A money handling machine comprising a

coin tray, means including a plurality of ejectors for ejecting the coins from the tray, rocker arms for operating the ejectors, a shiftable keyboard carrying a plurality of keys adapted to be depressed, and a plurality of projections formed on each key, certain of said projections on the keys engaging certain of the rocker arms when the keyboard is in one position and others of the projections engaging other of the rocker arms when the keyboard is in shifted position, the projections operating the rocker arms when the keys are depressed for ejecting the coins from the tray.

6. A money handling machine comprising a coin tray, means including a plurality of ejectors for ejecting the coins from the tray, spaced rocker arms for operating the ejectors, a shiftable keyboard carrying a plurality of keys adapted to be depressed, and a plurality of projections formed on each key, certain of the projections on the keys engaging certain of the rocker arms when the keyboard is in one position and others of the projections engaging other of the rocker arms when the keyboard is in shifted position, those projections not engaging the rocker arms being received in the spaces between said rocker arms when the keys are depressed to operate the rocker arms to eject the coins.

7. A money handling machine comprising a coin tray, means for ejecting the coins from the tray, a bodily shiftable keyboard for operating the coin ejecting means, and means for shifting the keyboard.

8. A money handling machine comprising a coin tray, means for ejecting the coins from the tray, a shiftable keyboard for operating the coin ejecting means, and a lever for shifting the keyboard.

9. A money handling machine comprising a coin supporting tray, means for ejecting the coins from the tray, a bodily shiftable keyboard for operating the coin ejecting means, and means for holding the keyboard in its shifted positions.

10. A money handling machine comprising a coin supporting tray, means for ejecting the coins from the tray, a bodily shiftable keyboard for operating the coin ejecting means, and means for shifting the keyboard and holding the same in its shifted positions.

11. A money handling machine comprising a coin supporting tray, means for ejecting the coins from the tray, a shiftable keyboard for operating the coin ejecting means, means for holding the keyboard in one of its shifted positions, means for moving the keyboard to its other position, and means for automatically returning the keyboard to its first position upon depression of a key.

12. A money handling machine adapted to be operated upon two different bases, comprising a tray for supporting coins, coin ejecting means, and a shiftable keyboard for operating the coin ejecting means, means for

holding the keyboard in one position for normally operating upon one basis, and means for shifting the keyboard to secure a single operation on the other basis.

5 13. A money handling machine adapted to be operated upon two different bases comprising a tray for supporting coins, coin ejecting means, and a shiftable keyboard for operating the coin ejecting means, means for holding the keyboard in one position for normally operating upon one basis, means for shifting the keyboard to secure a single operation on the other basis, and means for returning the keyboard to its first position for 10 operation of the machine on its normal basis.

14. A money handling machine adapted to be operated upon two different bases comprising a tray for supporting coins, coin ejecting means, and a shiftable keyboard for operating the coin ejecting means, means for holding the keyboard in one position for normally operating upon one basis, means for shifting the keyboard to secure a single operation on the other basis, and means for automatically 20 returning the keyboard to its first position for operation of the machine on its normal basis upon depression of a key.

15. A money handling machine adapted to be operated upon two different bases, comprising a tray for supporting coins, means for ejecting the coins, and a shiftable keyboard for operating the coin ejecting means, means for normally operating the machine on one basis, and yieldable means connected to the 30 keyboard whereby the same may be shifted for a single operation on the other basis.

16. A money handling machine comprising a tray for supporting coins, means for ejecting the coins from the tray, a shiftable keyboard for operating the coin ejecting means, a lever, and a flexible connection between the 40 lever and keyboard, the keyboard being shifted upon operation of the lever.

17. A money handling machine adapted to be operated upon two different bases comprising a tray for supporting coins, means for ejecting the coins, and a shiftable keyboard for operating the coin ejecting means, and flexible means for shifting the keyboard 50 whereby the keyboard may be set for normal operation upon one basis and may be set for a single operation upon the other basis.

18. A money handling machine comprising a coin tray, means including a plurality of 55 ejectors for ejecting the coins from the tray, a shiftable keyboard carrying a plurality of keys which when depressed operate the coin ejectors, each key being provided with a designating mark, the key when depressed while the keyboard is in one position delivering coins from the tray in such an amount equal to the difference of the designating mark on the key and one dollar and when depressed while the keyboard is in the other position to 60 deliver coins from the tray equal to the 65

amount of the designating mark on the key, means for setting the machine so that when the keyboard is in its first mentioned position change will be delivered from the fraction of a dollar, and means for locking said last mentioned means in inoperative position when the keyboard is in its second mentioned position.

19. A coin handling machine comprising a coin tray, coin ejecting mechanism, a shiftable keyboard, keys carried by the keyboard for operating the coin ejecting mechanism, and for normally delivering coins from the tray as change from a dollar, means whereby the coin ejecting mechanism may be operated to deliver change from the fraction of a dollar, and means carried by the keyboard for locking said last mentioned means in inoperative position.

20. A money handling machine comprising a coin tray, means for ejecting the coins from the tray, and a keyboard, said keyboard and ejecting means being relatively adjustable whereby when in one adjusted position, upon operation of the keys of the keyboard, the ejecting means will be operated for ejecting certain combinations of coins from the tray and when in another adjusted position, upon operation of the keys carried by the keyboard, the ejecting means will be operated for ejecting other combinations of coins from the tray.

21. A money handling machine adapted to be operated upon two different bases to liberate different combinations of coins, means for normally operating the machine on one basis, means for securing a single operation of the machine on the other basis, and means whereby the machine is returned to the first basis after said single operation on the other basis.

In testimony whereof I hereunto affix my signature.

EDWARD J. BRANDT.
